(57) CLAIM

The ornamental design for a heated cutting tool, as shown and described.

DESCRIPTION

FIG. 1 is a front perspective view of a heated cutting tool; FIG. 2 is a rear perspective view of the heated cutting tool shown in FIG. 1;

FIG. 3 is a front view of the heated cutting tool shown in FIG. 1;

FIG. 4 is a rear view of the heated cutting tool shown in FIG. 1;

FIG. 5 is a top view of the heated cutting tool shown in FIG. 1;

FIG. 6 is a bottom view of the heated cutting tool shown in FIG. 1;

FIG. 7 is a right side view of the heated cutting tool shown in FIG. 1; and,

FIG. 8 is a left side view of the heated cutting tool shown in FIG. 1.

The broken lines shown in the FIGS. are of the remainder of the heated cutting tool, provided for illustrative and environmental purposes only and form no part of the claimed design.
